(57) **CLAIM**

The ornamental design for a conduit securement device, as shown and described.

DESCRIPTION

FIG. 1 is a perspective view of a conduit securement device of the novel design.

FIG. 2 another perspective view of the design of FIG. 1.

FIG. 3 is a front side view of the design of FIG. 1.

FIG. 4 is a back side view of the design of FIG. 1.

FIG. 5 is a top side view of the design of FIG. 1.

FIG. 6 is a bottom side view of the design of FIG. 1.

FIG. 7 is a left side view of the design of FIG. 1.

FIG. 8 is a right side view of the design of FIG. 1.

FIG. 9 is a perspective view of the design of FIG. 1 with the conduit straps in an unfastened position.

FIG. 10 is another perspective view of the design of FIG. 1 with the conduit straps in an unfastened position.

FIG. 11 is a perspective view of the design of FIG. 1 with the wrist strap in an unfastened position.

FIG. 12 is another perspective view of the design of FIG. 1 with the wrist strap in an unfastened position.

FIG. 13 is a top view of the design of FIG. 1 with the wrist strap in an unfastened position; and,

FIG. 14 is a bottom view of the design of FIG. 1 the wrist strap in an unfastened position.

Portions shown in broken lines form no part of the claimed design.

1 Claim, 14 Drawing Sheets
